COMBINATION TOOL STAND AND CASE

Laurence H. Drophman, Chicago, Ill.

Application January 2, 1947, Serial No. 719,723

3 Claims. (Cl. 206—17)

1

This invention relates to portable apparatus for transporting and displaying tools and more particularly it relates to a combination drill case and stand.

It is very desirable that a drill case be compact yet function as a stand while the drills are in use. Drill cases heretofore proposed may be relatively compact when closed but do not stand so that the drills are easily accessible to the operator. Likewise, drill stands now available which present the drills in a vertical, spaced position are not in compact unitary cases.

A principal object of this invention is to provide a unitary drill case and stand of novel and improved construction which is compact when closed, and by simply opening the case, a row or rows of tools such as drills carried therein are automatically moved into such position that each tool becomes readily accessible and upon closing the case, each row of tools is automatically aligned within the covers of the case.

It is also an object of this invention to provide a tool case which can be used not only to carry tools but also as a bench stand. Another object of the invention is to provide a case in which tools may be securely carried and stored so as to present the tools at all times for use in pre-arranged order and to provide a stand for the arranged tools. These and other objects will become apparent as the description of my invention proceeds.

In the accompanying drawings which form a part of this specification, similar reference characters are used to designate corresponding elements in the various views wherein:

Figure 1 is a perspective of my case and stand with the covers open and showing the radially aligned panels or retaining means;

Figure 2 is a top view of the case and stand shown in Figure 1;

Figure 3 is a side view of the closed case;

Figure 4 is a top view with the case closed;

Figure 5 is a fragmentary view in perspective showing the details of the hinge assembly;

Figure 6 is a fragmentary view of the hinge assembly in Figure 5 with parts removed;

Figure 7 is a top view of the stop means shown generally at 29 in Figures 1, 2 and 4 which is adapted to align the holders in the open case; and

Figures 8 and 9 show details of modifications of the spacer elements adapted to align the panels or holders.

Broadly my device, which will be described adapted for holding drills, comprises a pair of hinged covers having one or more drill holders

2

or panels mounted upon the cover hinge. Means carried by the cover elements and the hinge can be provided to automatically position, space, and secure the drill holder or panels radially between the covers with the drills in a substantially vertical position upon opening the case. The two halves of the case cooperate with a holder and together they give rigidity to the open stand.

As the case is opened spacers, carried by the covers or the holder but free to move with reference to the other, swing the holders so that they are in a fan-like position, the spacing of which is determined by a stop key mounted on the case hinge. When the case has been opened to the fullest degree, or so that the angular portion of the front and back halves of the cases are back to back, the drill holders are in a fixed open position, enabling the user easily to see and select any drill he wishes. Thus the device will stand in an upright vertical position with the drill stand exposed and the case is out of the way.

In the drawings, 10 and 11 designate the two halves of a clam shell case hinged along adjacent edges 12 and 12a and pivoted about the hinge pin 13. A portion of the edges 12 and 12a may be rolled to engage the pin 13 and these hinge portions are designated as 10a and 11a in the drawing. The periphery of the one half of the case 10 is provided with ledge or bead 14 so that the edge 15 of 11 may clamp with the front cover 10 to keep the case closed but adapted to be conveniently opened. The two cover elements 10 and 11 are designed and hinged so as to permit their opening more than 180 degrees before the inclined edges 12 and 12a abut as shown in Figures 1, 2 and 3, the edges 12 and 12a serving as stops for the rearward swing of the clam shell covers.

Depending upon the number of drills or tools to be housed within the combination drill case and stand, one or more drill panels may be mounted with the case 10—11. The illustrated embodiment includes two panels 16 and 16a. In any event, each panel is pivotally mounted on its rearward edge on the hinge pin 13. A portion of the rearward edge of the panel may be rolled to engage the pin 13.

In the illustrated embodiment each of the drill panels 16 and 16a has a ledge 17 at its upper edge which is provided with an upper support comprising a series of drill sockets 18 of graduated diameter. The sets of holes or sockets 18 are formed in the metal of the exact size to receive readily the end of the tools intended to be placed therein. A lower support 19 is adapted

to retain the lower end of the drills within the sockets 18. Intermediate socket guide 20 having sockets 21 corresponding to those in the ledge 17, likewise may be disposed below the ledge 17 and above the inclined support 19. If desired sockets 18 may be provided by drilling a bar stock and fixing it to the panel 16 or 16a. Likewise, the intermediate support 20 can be consolidated with either the upper or lower supports or omitted entirely. Likewise the lower support 19 may comprise a folded or crimped portion of the panel itself and may be substantially parallel to the socket means 18.

Each of panels 16 and 16a is mounted upon the common hinge pin 13 by means of the folded hinge elements 22 and 23 and 22a and 23a which are integral with the panels 16 and 16a. These hinge elements are spaced on the panel so that they may be interchangeably mounted on the hinge rod or pin 13. Thus, panel 16 is provided with hinge elements 22 and 23 and panel 16a includes complementary hinge elements 22a and 23a. Each panel includes slits or ways 24, 25 and 26 which are adapted to receive the aligning spacers and stop key designated generally by the numerals 27, 28 and 29, respectively. The spacers and stop key include a tongue or equivalent means 30 adapted to engage each respective panel and coat to dispose the panels radially between the covers 10 and 11. The spacers 27 and 28 are fixed by upstanding portion 33 to edges 12a and 12, respectively, and stop key 29 is pivotally mounted on the hinge rod 13.

Referring to Figures 5 and 6 the panels 17 and 17a are mounted on hinge rod 13. The spacer element 28 has one end 33 fixed to the cover 11 along the edge 12. The disc portion or arm 32 of the spacer 28 is in the plane of the slit or key way 26 in panel 16 and the tongue or stop 30 engages the end of the slit 26 thereby serving to rotate the panel 16 about the hinge rod 13 when the covers 10 and 11 are separated. The complementary panel 16a is likewise mounted upon the hinge rod 13 and is provided with a spacer or aligning means 27 which is a mirror image of the spacer 28. This spacing means 27 is fixed or carried by the rear cover 10 on the edge 12a. The disc portion of the spacer 27 is in the plane of the slit 24 in the lower part of the panel 16a. As in the case of the spacing element 28 a tongue or stop 30 on the spacing element 27 engages the panel or an extension thereof and rotates the panel about the hinge rod 13 when the covers are separated.

A stop element or key 29 is rotatably carried by the hinge rod 13 in the plane of the slots 25 and 25a in the panels 16 and 16a. Although the embodiment illustrates the quadrant stop or key 29 intermediate the aligning elements 27 and 28, it is contemplated that the stop means 29 may be in either the upper or lower position. The extremities of the key 29 have stops or tongues 30 which are adapted to engage the face of the panels 16 and 16a for example, adjacent the end of the slots 25. This quadrant spacing device 30 limits the spacing of the panels 16 and 16a, which are then spaced equidistant when the covers 10 and 11 are rotated about the hinge rod 13 and the spacers 27 and 28 tend to separate the panels. It will be recognized that when more than two panels are mounted upon the same hinge rod, a spacing element will be necessary for each panel and a stop means corresponding to key 29 having stops 30 which subtend greater or lesser angles than shown will be used.

If desired, one or more additional panels may be supported on the upper portion of the hinge rod 13 between the drills mounted in the sockets 18 and 18a of the panels 16 and 16a. Thus the smallest graduated set of drills might be carried conveniently in such an auxiliary panel and increase the capacity and usefulness of the combination case and stand. Such auxiliary panel would be spaced by a pair of elements corresponding to spacers 27 and 28.

Figure 6 illustrates the details of the spacer 28 in position and corresponds to the spacer 28 in Figures 1 and 4. This spacer comprises upstanding edge 33, arm 32 and stop or arm extension 30.

In Figure 7 the details of one embodiment of the stop means 29 are shown. The illustrated stop means includes a quadrant or disc-like section 29a pivoting means 29b and tongues or stops 30. It should be understood, however, that means equivalent to the tongues 30 such as the raised portions 36 of Figures 8 and 9, may be substituted so long as they function to restrict the movement of the key 29 through the slot or slots on the panels.

Figures 8 and 9 are two views of another modification of the spacer 27 and 28. These spacers comprise an arm 34, an upstanding edge 35 adapted to be tack-welded or otherwise fixed to the inner edges 12 and 12a of the covers 10 and 11, and also includes a second upturned portion 36 which serves to engage the face of the panels adjacent the slots or extensions carried by the panels.

If desired the stock in the region of the hinge pin 13 can be of substantial thickness or diameter and the functions of the spacers 27-28 and the key stop 29 can be performed by cut-away portions of the cover and panel hinge assembly. Thus complementary portions of adjacent hinge elements being suitably undercut will permit rotation relative to the other for a predetermined extent to swing the holders out between the covers and to control the spacing of the holders in fixed relation.

In summary, the covers 10 and 11 are mounted on the hinge rod 13 and carry spacer 27 on the front cover and spacer 28 on the rear cover fixed to edges 12a and 12. These spacers are adapted to pass through the slots 24, and 25 in the panels 16 and 16a until the tongues 30 engage the face of the panel adjacent the slot. The stop means 29 is rotatably mounted upon the hinge rod 13 and also is provided with tongues 30 which engage the reverse side of the panels 16 and 16a and restrict the movement of the panels as they are urged apart by the spacers 27 and 28.

From the above description it will be apparent that I have provided a combined tool stand and case which is compact when closed, requiring the minimum amount of space for storing; it opens into an upright stand with the drills all in a vertical position and with the holders so spaced that all the drills are easily distinguishable and accessible to the user; and due to the radial spacing there is no tendency for the open stand to fall. However, if the user wishes to select a drill without setting the case down, he can merely open the case and hold it by either the front or back section of the case. A particular advantage is that the case cannot be opened without spreading the holders apart.

Although specific embodiments of my invention have been described, it should be understood that this is by way of illustration only.

and that the invention is not limited thereto. From the above description, modifications will become apparent to those skilled in the art and such modifications and alternatives are contemplated as coming within the scope of the invention as defined by the appended claims.

I claim:

1. In a combination tool stand and case, a first cover member comprising a flat right quadrilateral wall with a peripheral flange extending inwardly from the top, front, bottom and rear edges thereof, the flange on the bottom edge extending perpendicular to the wall and the flange on the rear edge extending obtusely to the wall, a second cover member comprising a second flat right quadrilateral wall with a peripheral flange extending inwardly from the top, front, bottom and rear edges thereof, the flange on the bottom edge extending perpendicular to the wall and the flange on the rear edge extending obtusely to the wall, the flanges extending inwardly from the bottom edges of said walls providing a footing for the stand and case, an axial hinge means including a hinge rod joining adjacent edges of said obtusely extending flanges, drill support panel means hinged by one edge to the said hinge rod for rotation thereon between said cover members and adapted to be enclosed wholly within said cover members when said peripheral flanges are in juxtaposition, at least two open-ended slots in said support panel means and spaced longitudinally of said hinge means, a first arcuate web means having one end fixed to said first cover member and passing through a first of said slots, a stop means on said arcuate web means remote from said first cover member and adapted to engage a portion of said panel means adjacent said first slot, a second arcuate web means fixed to said second cover member and passing through a second of said slots, and stop means on said second arcuate web means remote from said second cover member and adapted to engage a portion of said panel means adjacent said second slot.

2. In a combination drill stand and case, a pair of cover members each comprising a flat right trapezoidal wall with a peripheral flange means extending inwardly therefrom, the flanges at the top, front, and bottom edges of said walls being perpendicular to the wall and the flange at the rear edge of each said wall extending obtusely thereto, the flanges along the bottom edges of said walls forming a base for said case, a vertical hinge means including a hinge rod joining said obtusely extending flanges on the rear edges of said walls, a pair of drill support panels hinged to said rod and adapted to be wholly enclosed within said cover members, vertically spaced open slots in each of said support panels extending in planes perpendicular to the axis of said hinge rod, at least one slot in each support panel being in alignment in the same plane with a corresponding slot in the other panel, a floating arcuate web means pivoted to said hinge rod and passing within said aligned slots, a second arcuate web means fixed to the first of said cover members and passing within

another of said slots in a first of said panels, a third arcuate web means fixed to the second of said cover members and passing within another of said slots in a second of said panels, the length of said slots being greater than the radial extent of the respective arcuate web in said slots, a pair of angularly spaced stop means carried by said floating arcuate web adapted to engage the remote surfaces of the said drill support panels, and stop means carried by each of said fixed arcuate web means adapted to engage the respective panel on a surface remote from the cover member to which the corresponding arcuate web is fixed.

15 3. A combination drill case and stand comprising a pair of hinged cover members, each of said cover members comprising a flat right quadrilateral wall with peripheral flange means extending inwardly therefrom, the flange extending from top, front, and bottom edges of said walls being perpendicular to the said wall and the flange at the rear edge of each said wall extending obtusely thereto, a hinge rod joining the obtusely extending flanges of said cover members, a plurality of drill support panels disposed between said cover members, said panels being pivotally mounted on said hinge rod and being adapted to be rotated about an axis collinear with said hinge rod, vertically spaced open slots in each of said support panels extending in planes transverse to the axis of said hinge rod, an additional slot in each support panel in alignment with a corresponding additional slot in another support panel, spacer means fixed to each of said cover members and adapted to become operative for rotating said support panels about said hinge rod after the cover members have been separated at their front flanges a predetermined angular distance, and angular stop means freely pivoted to said hinge rod and operating in said additional aligned slots to oppose the rotation of said support panels toward the respective cover member by said spacer means, whereby upon separating the cover members, the support panels are disposed angularly from said members and from each other in a rigid spaced array, thereby exposing the drill support panels.
